SPLAY BEAD

Randolph L. Dietrich, Los Angeles, Calif.

Application September 5, 1939, Serial No. 293,321

9 Claims. (Cl. 72—98)

The present invention relates to improvements in splay beads and particularly to a splay bead incorporating a plastering element tieable with a plastered wall adjacent a window or door opening.

One of the important objects of the invention is to provide a splay bead in conjunction with a window or door opening and the plastered part of the wall adjacent such opening.

Another object of the invention is to provide in a splay bead construction a part having a joint of leverage in relation to the splay bead proper to accommodate the application of the head to a trim member and a building member where irregularities exist between the two.

A further object of the invention is to provide in a splay bead construction improved strengthening means for maintaining a fixed relation of the beads' edges and at the same time providing improved means for bonding or coalescing the plaster comprising the plaster splay to the plaster comprising the wall.

A still further object of the invention is to provide in a splay bead structure a rolled edge portion over which the tools of a plasterer may operate in joining the plaster of the splay and the plaster of the wall.

Yet a still further object of the invention resides in the improved application of plaster in a splay bead and the anchoring thereof therein.

Yet another object of the invention resides in the novel method of constructing the metal portion of the bead whereby improved bracing and bonding means are provided.

The invention further relates to an improved sheet metal article of manufacture for the purposes stated.

Still other objects, features and advantages of invention, including the novel combination of associated parts, will hereinafter appear.

Referring to the drawing, the brief description of figures includes Figure 1, which is a perspective view illustrating the application of the splay bead to a conventional building structure; Figure 2 which is a perspective view of a portion of the length of the metal part of the splay bead per se; and, Figure 3 which is a cross section of the completed structure.

Referring in detail to the drawing the splay bead number 5, separately shown in Figure 2, consists of a single strip of sheet metal which is bent over upon itself along a straight line 6 which extends in a parallel spaced relation to its long edges and desirably at about the mid-width of the strip thus provides it with a basal,

double ply portion, one ply 7 of which is continued in a flat plane to form a basal flange 8, the other ply 9 being directed right angularly away from the basal part along a line 10 thus producing a run 11 which terminates in a flange 12 which overhangs that face of the run 9 which is adjacent to the basal flange 8.

The part of the strip having the angular bend 10 is provided with pairs of slits cut transversely through its angular portion and then the metal strips 15 between the paired slits are bent outwardly from the angle 10 thus furnishing a series of struts which stabilize the metal run 11 in its right angularly directed position. The metal strips 15 are bent to shorten them, desirably being corrugated, as shown, thus not only strengthening them but producing a better anchorage for the plastering.

Speaking of the novel method whereby the metal portion of the structure is produced, the strip of sheet metal forming the same is first longitudinally bent to a right angle. It is then transversely slit across said angle, whereupon the stock of metal between the slits is foreshortened (by corrugating or otherwise bending it) thereby producing the irregular hypotenuse strip or strips 15 that performs a bracing function between the two metal sides that subtend the angle. Lastly, by a backward rolling of the edge portion of the side 11, the flange 12 is produced.

In Figures 1 and 3 the strip 5 is shown associated with a window jamb 25, room wall 26 consisting of the plaster portion 27 and the underlying lath portion 28, and stud 29, the basal flange 8 being interposed between said stud and the lath portion of said wall and the double ply portion of the strip overlying an edge surface of the jamb edge surface of the stud 29. In putting the strip in place its double ply portion is first secured to the jamb or trim member 25 by nails 30, one of which are shown in Figure 1. Then the basal flange 8 is secured to the stud 29 by nails 31 in whichever direction and to whatever extent may be necessary to seat said flange upon the edge portion of said stud, it being understood that the edge faces of said stud and jamb do not always line in the same plane. The attached, two ply portion of the strip affords a secure leverage from which the flange portion 8 thereof may be deflected to the desired extent, as aforesaid.

After the strip has been attached in the manner stated the lath portion 28 of the wall will be secured in place by nails 32 overlying to a considerable extent the basal flange 8. Then

plastering 33 will be filled into the angle between the sheet metal runs 9 and 11 and also the room wall section shown will be completed by applying the layer 27 of plaster over the lath 28.

Slitting the strip and subsequently forming the struts or braces 15 between the slits produces openings 34 through the strip, thus affording a means for bonding or coalescing the plaster part 33 of the splay with the plaster wall 27.

A window sash 35 is shown in the wall opening provided therefor, but obviously the splay bead structure is applicable to a room wall having in it openings other than window openings.

It is to be understood that the present disclosure is for the purpose of illustration only and that the invention includes all modifications and equivalents that fall within the scope of the subject matter claimed.

What is claimed is:

1. A splay bead member consisting of a sheet metal strip rebent upon itself along a line in a parallel spaced relation to its long edges, thus providing in said strip a double ply of metal, one of the plies being extended beyond the other in the same plane, thus providing a flat basal flange, and the other of said plies being right angularly deflected away from said basal flange along a straight longitudinal line which extends in a parallel spaced relation to the long outer edge of said basal flange, the strip being provided with pairs of transverse slits which extend through the part thereof which is right angularly bent, the metal between the paired slits being bent outwardly from the angle thus forming struts extending from said basal flange to the right angularly extending ply.

2. The subject matter of claim 1 and, said struts having bends whereby their lengths are shortened and additional anchorage is furnished for plaster.

3. The subject matter of claim 1 and, said struts being corrugated thus shortening them and affording additional anchorage for plaster.

4. A splay bead member consisting of a sheet metal strip rebent upon itself along a line in a parallel spaced relation to its long edges, thus providing in said strip a double ply of metal, one of the plies being extended beyond the other in the same plane, thus providing a flat basal flange, and the other of said plies being right angularly deflected away from said basal flange along a straight longitudinal line which extends in a parallel spaced relation to the long outer edge of said basal flange, the strip being provided with pairs of transverse slits which extend through the part thereof which is right angularly bent, the metal between the paired slits being bent outwardly from the angle thus forming struts extending from said basal flange to the right angularly extending ply, said right angularly bent portion of the strip having its free edge furnished with a longitudinal flange which is directed toward the single ply side of said basal run, thereby furnishing a finished edge along the line of the juncture of said flange with the strip portion of which it forms a part.

5. The combination with a plastered wall, a trim therefor, a frame member to which said trim is applied, and a beveled plaster splay adjacent to an opening in a wall; of a sheet metal splay bead having a right-angularly bent portion for containing said beveled plaster splay whereby to furnish a finished independent plastered terminus for said plastered wall, one of

the limbs of said right-angularly bent portion being rebent upon itself to in combination with such limb form a basal part attachable in a flatwise manner to the trim adjacent said opening, said rebent portion being extended beyond

5 said limb in the same plane whereby to provide a means for securing said bead to said frame member, the other limb forming said right-angularly bent portion forming a stop against 10 which the edge of said plastered wall abuts, the latter limb having a rolled free edge portion extending into said plastered wall over which the tools of a plasterer operate in joining the plaster wall to the plaster splay, and anchor means for 15 securing plaster to said wall and to said beveled plaster splay of which said sheet metal splay bead forms a part.

6. In a device of the kind described, a sheet metal splay bead including a right-angularly bent portion one limb of which forms an abutment for a plastered wall on opposite outer side of such limb, and the other limb comprising a basal flange attachable to a trim member adjacent a door opening, said basal flange having 20 a rebent portion underlying said basal flange and projecting beyond said wall abutting portion to form attaching means for securing it to a frame member to which said trim is united, and a plaster splay contained in the corner space provided 25 by said right-angularly bent portion to independently adjoin said plastered wall, said splay forming a terminal bevel of said plastered wall, there being openings in said one limb for coalescing said splay to said wall, said one limb 30 having its free edge furnished with a longitudinal flange which is directed toward said attaching means which is secured to said frame member, thereby furnishing a finished edge along the line of juncture of said flange with the 35 limb of which it forms a part over which the tools of a plasterer operate in joining the plastered wall to the plaster splay.

7. In a wall structure, a splay bead member 40 consisting of a sheet metal strip rebent upon itself along a line in a parallel spaced relation to its long edges thus providing in said strip a double ply of metal, one of the plies being continued in the same plane thus providing a flat basal flange and the other said ply being right-angularly deflected along a straight longitudinal 45 line, the angle thus formed by the latter two plies forming a corner, a separate plastering element in said corner comprising a beveled plaster splay, a plastered wall abutting against the face 50 of said right-angularly deflected ply which is opposite to said plaster splay, the latter ply having through it slots occupied by plaster which 55 forms bonds between the plaster of the wall and the plaster of said plastered splay.

8. The subject matter of claim 7 and, said right-angularly deflected ply portion being provided with pairs of transverse slits, the metal between slits being bent outwardly into the corner occupied by said beveled plaster splay.

9. In a wall structure, a splay bead member 60 consisting of a sheet metal strip rebent upon itself along a line in a parallel spaced relation to its long edges, thus providing in said strip a double ply of metal, one of the plies being extended beyond the other in the same plane, thus providing a flat basal flange, and the other of said plies being right-angularly deflected away from said basal flange along a straight longitudinal line which extends in a parallel spaced 65 relation to the long outer edge of said basal

flange, said right-angularly bent portion of the strip having its free edge furnished with a longitudinal flange which is directed toward the single ply side of said basal run, thereby furnishing a finished edge along the line of the juncture of said flange with the strip portion of which it forms a part, said right-angularly bent portion of the strip providing an abutment, a plaster wall engaging said abutment, said longitudinal flange carried by the free edge portion 10 being directed into said wall, a plaster splay con-

5 tained in and filling the corner formed by the double ply metal and right-angularly bent portion, said plaster splay being beveled and forming a finished additional terminus for said plaster wall, said splay bead member having openings through it, and plaster occupying said openings thereby forming a bond between the plaster in the corner of said splay bead member and the plaster in said wall.

RANDOLPH L. DIETRICH.
